GIFT BOX

Gilbert S. Gruber, Somerville, and Kathryn N. Delany, Brookline, Mass., assignors to Oxford Products Corp., Boston, Mass., a corporation of Massachusetts

Application December 2, 1948, Serial No. 149,918

Term of patent 7 years

(Cl. D58—11)

To all whom it may concern:

Be it known that we, Gilbert S. Gruber, and Kathryn N. Delany, both citizens of the United States of America, and residing respectively at Somerville, Massachusetts, and Brookline, Massachusetts, have invented a new, original, and ornamental Design for Gift Box, of which the following is a specification, reference being had to the accompanying drawing, forming part thereof.

Fig. 1 is a plan view of a gift box, showing our new design;

Fig. 2 is a side elevation thereof; and

Fig. 3 is a perspective view showing the opened gift box.

The characteristic features of my design reside in those portions shown by means of full lines in the drawing.

We claim:

The ornamental design for a gift box, as shown and described.

GILBERT S. GRUBER.
KATHRYN N. DELANY.
